UNITED STATES PATENT OFFICE.

LEWIS H. LAMONT, OF OAK PARK, ILLINOIS.

THERMOSTATICALLY-CONTROLLED HEATING ELEMENT.

Application filed October 24, 1925. Serial No. 64,503.

This invention relates to means for initially heating the fuel supply for internal combustion engines to assist in starting a cold engine.

5 It is an object of this invention to provide an improved fuel heating system adapted to initially heat the fuel to approximate summer operating conditions for starting a cold motor. It is well known that after starting 10 a motor it is a simple matter to maintain summer temperatures within the motor enclosure, but the initial starting with cold fuel requires a very much richer carburetor adjustment in winter as compared with summer. Heretofore various forms of fuel vaporizing systems have been suggested wherein a charge of fuel is heated to such a high point as to cause at least partial vaporization, the vapor passing into the manifold to 15 give a richer starting mixture. The dangers inherent in such a procedure will be apparent. The present invention does not contemplate vaporization of the fuel but relates to bringing the fuel in a carburetor to a 20 temperature approximating summer conditions wherein the fuel will be properly vaporized or atomized by the normal action of the carburetor nozzles.

It is also an object of this invention to 25 provide a device of the class described adapted to be brought into action by the normal operation of the starting choke valve on the carburetor and to automatically cut out upon the fuel in the carburetor reaching the 30 desired temperature.

It is a further object of this invention to 35 provide a simple and easily manufactured device that will be entirely safe in the hands of an unskilled user.

40 Other and further important objects of this invention will be apparent from the disclosures in the specification and drawings.

The invention (in a preferred form) is 45 illustrated in the drawings and hereinafter fully described.

On the drawings:

Figure 1 is an elevation of a device embodying the features of this invention as applied to a carburetor including the control interconnecting the device with the carburetor choke;

Fig. 2 is an enlarged longitudinal section through the device;

Fig. 3 is a bottom view with the switch 50 compartment cover removed;

Fig. 4 is a section on the line IV—IV of Figure 2;

Fig. 5 is a section on the line V—V of Figure 2; and

Fig. 6 is an elevation showing the modified hook-up of the heating device control.

As shown on the drawings:

A carburetor 10 is shown in Figure 1 for the purpose of illustrating the attachment of and control for the device of this invention, the carburetor float chamber drain opening being indicated at 11 and the choke lever at 12, a rod 13 extending to a spring returned pull button 14 on an instrument board 15. The switch of the device of this 70 invention is also connected to the pull button 14 by the rod 16 so as to be actuated in unison with the carburetor choke. A casing 17 is provided with a fuel chamber 18 having an outlet 18^a connected to the carburetor 75 drain 11, and a switch chamber 19 closed at the bottom by a cover 20. The fuel chamber 18 contains a heating element 21 having a lead-in terminal 22 insulated from the casing, the return lead 23 from the heating element being grounded to the plug 24 on which the heating element is mounted.

80 The switch mechanism proper is mounted on an insulating base 25 secured within the switch compartment 19 with a space between 85 the insulating base and the bottom of the fuel compartment to provide room for a thermostatic metal strip 26 which is flat against the base 25 when hot. This strip is shown in dotted lines as warped upwardly 90 by low temperature conditions.

95 Mounted on the lower side of the insulating base are two spaced terminals 27 and 28, the terminal 27 being connected by the wire 29 to the heating element terminal 22 while the second terminal 28 receives the live wire 30 from the source of electrical energy, the return being grounded through the casing and carburetor. Each terminal 27 and 28 clamps one of a pair of spring 100 switch contacts 31 in opposed relationship, the blades of the contacts being set at a slight angle to make a forced contact with the bridging member 32 which comprises a U-shaped bar pivoted at 33 to a support 34 105 having lugs 35 bent over to form limiting stops in the open position of the bridge 32. A spring 36 is secured at one end to the bend of the bridge 32 the other end being attached to a second U-shaped member 37 110

which is also pivoted at 33, lugs 38 being provided on the support 34 to limit the outward movement thereof. These two **U** members together with the spring comprises a snap-over mechanism suddenly actuating the switch bridge when the spring center line passes the axis of the pivots 33, the accelerated motion thus imparted to the bridge on the closing thereof serving to force it between the spring switch contacts which are disposed at a slight angle.

A vertically mounted stirrup 39 of insulating material is guided in a slot 40 of the base 25, holes in the ends of the stirrups receiving lugs 42 struck from the **U** member 37 so that the stirrup controls the snap-over mechanism. The top of the stirrup rests beneath the end of the thermostatic strip which, when warm, holds the stirrup down so that the switch will be open. If the temperature conditions are such that the thermostatic strip is warped into the position shown in dotted lines in Figure 2, the switch may be manually closed by lifting the stirrup. The switch can be closed at any time even against the action of the flat thermostatic strip but under such circumstances the switch is immediately reopened upon the release of the manual control due to the spring like action of the thermostatic strip when flattened out in response to the designed temperature.

The manual control referred to comprises a bell crank pivoted at 43, one arm of 44 which extends under the top of the stirrup. A second arm 45 is formed to engage between balls of a pull chain 46 connected to the rod 16 previously mentioned. Pulling on this chain will lift the stirrup regardless of the position of the thermostatic strip and will therefore close the switch. A spring arm 47 engages a third arm 48 of the bell crank and serves to normally return the bell crank to the position shown in the drawings.

The modified form of Figure 6 relates to connecting the pull chain 46, of the manual control for the switch, to the choke lever 12 through the medium of a spring 49 which permits the thermostatic strip to maintain the switch open, when the choke is closed above a designed temperature to prevent danger of overheating the fuel in hot weather.

In operation the device of this invention may if desired be operated each time the choke button is pulled out. If the fuel in the carburetor is already at the desired temperature the heater will be on only as long as the choke is pulled out as the thermostat serves as a spring to return the switch to

open position. On the other hand if the temperature of the fuel is below the desired point the thermostat will be warped upwardly so that when the switch is closed by the operation of the choke it remains closed until the fuel in the carburetor is heated to the desired point, even though the choke button is immediately released.

I am aware that many changes may be made and numerous details of construction may be varied through a wide range without departing from the principles of this invention, and I therefore do not purpose limiting the patent granted otherwise than necessitated by the prior art.

I claim as my invention:

1. A heating device of the class described comprising an electric heating element and a snap-over switch controlling the current supply therefor, said switch comprising a pair of oppositely extending **U** members pivoted at a common axis, a spring connecting said **U** members, insulated terminals adapted to be bridged by one of said members, a thermostatic member adapted to mechanically open said switch, and a manual control for closing said switch against the action of the thermostatic member.

2. In a device of the class described, an electric heating element, a switch therefor, a thermostat adapted to open said switch at a predetermined temperature, and a manual control for closing said switch comprising a bell crank one arm of which is adapted to receive a pull chain and another arm of which actuates the switch mechanism in opposition to the thermostat.

3. In a device of the class described an electric heating element, a switch controlling the same, an insulated member for direct actuation of said switch in either direction, a thermostat adapted to act in one direction on said insulated member, and a bell crank adapted to act in the opposite direction on said member.

4. In a device of the class described an electric heating element, a switch controlling the same, an insulated member for direct actuation of said switch in either direction, a thermostat adapted to act in one direction on said insulated member, a bell crank adapted to act in the opposite direction on said member, and a yielding connection from said bell crank to the choke valve of a carburetor whereby the switch will be actuated in unison therewith.

In testimony whereof I have hereunto subscribed my name.

LEWIS H. LAMONT.
